UNITED STATES PATENT OFFICE.

SOPHIA L. CROWNFIELD, OF NEW YORK, N. Y., ASSIGNOR TO CHENEY
BROTHERS, OF SOUTH MANCHESTER, CONNECTICUT, A CORPORA-TION OF CONNECTICUT.

DESIGN FOR A TEXTILE FABRIC.

No. 38,571.

Specification for Design.

Patented May 14, 1907.

Application filed April 17, 1907. Serial No. 368,804. Term of patent 3½ years.

To all whom it may concern:

Be it known that I, SOPHIA L. CROWN-FIELD, a citizen of the United States, residing at the borough of Manhattan, New York city, in the county and State of New York, have invented a new, original, and ornamental Design for Textile Fabrics, of which the following is a specification, reference being had to the accompanying drawing, forming part thereof.

The figure is a plan view of the fabric, showing my new design.

I claim:

The ornamental design for a textile fabric,
as shown.

SOPHIA L. CROWNFIELD.
